CLAIM

The ornamental design for a removable support mount as shown and described.

DESCRIPTION

FIG. 1 is a top perspective view of a removable support mount in accordance with our new design;

FIG. 2 is a bottom perspective view of the removable support mount of FIG. 1;

FIG. 3 is a top view of the removable support mount of FIG. 1;

FIG. 4 is a bottom view of the removable support mount of FIG. 1;

FIG. 5 is a left-side elevation view of the removable support mount of FIG. 1;

FIG. 6 is a right-side elevation view of the removable support mount of FIG. 1;

FIG. 7 is a front elevation view of the removable support mount of FIG. 1; and,

FIG. 8 is a rear elevation view of the removable support mount of FIG. 1.

The broken lines in the drawings illustrate portions of the removable support mount that form no part of the claimed design.
